UNITED STATES PATENT OFFICE.

DAILY S. MOORE, OF CHICAGO, ILLINOIS.

IMPROVEMENT IN CAR-COUPINGS.

Specification forming part of Letters Patent No. 154,067, dated August 11, 1874; application filed June 27, 1874.

To all whom it may concern:

Be it known that I, DAILY S. MOORE, of Chicago, in the county of Cook and State of Illinois, have invented a new and Improved Car-Coupling; and I do hereby declare that the following is a full, clear, and exact description of the same, reference being had to the accompanying drawing forming a part of this specification, in which—

Figure 1 is a side elevation, partly in section, and Fig. 2 an end elevation.

The invention relates to that particular class of car-couplings wherein each draw-head is provided with a horn over which the link is passed.

The invention consists in novel means for automatically coupling with such a device, and also in means whereby the draw-head may be better adapted to this mode of coupling, all as hereinafter fully described.

AA represent two cars provided with draw-bars BB, which slide between bars CC on a rod, D, and against a spring, E. F is a coupling-link that is caused to fall over the horns bb, and thus connect together the draw-bars and their respective cars. This link rests in a cavity of draw-bar, and is provided at the other end with a chain, G, which is fastened rigidly at the upper end of a sliding bar, H, or might be attached to a car or to a hook or bracket thereon, enough length of chain being always left to allow the link to rest in the bottom of both draw-heads. When, however, a car is uncoupled and it is desired to hold up its link ready for coupling with another, a ring, g, or equivalent, at a suitable distance from the end of chain, is fastened over the vertical arm I of a right-angled staple, J, so as to raise the link to an angle of about forty-five degrees with a horizontal plane, in order to admit thereunder the horn of the opposite car's draw-bar.

The means which I employ to drop the link at the proper time are as follows: I employ the slide-bar H, having its lower end preferably provided with friction-roll h, and resting upon the top of draw-bar, while it has a side

loop or eye, h', that slides on the pin or staple-arm I. As the draw-bars yield to the shock of a collision, their inclined top surface a runs under the slide H, moves up the loop h', and throws off the chain-ring g, the link then falling by its own gravity over the horn of the opposite draw-bar.

In order to prevent the possibility of lateral displacement of the link while being held up, and to guide it squarely down upon the opposite draw-bar's horn, I make the draw-bars with high side walls a² a², which support the link on each side and guide it directly and accurately to its destination.

As it is very desirable that the link shall be caused to fall easily and quickly, I make a sharp transverse ridge, a³, passing just in rear of the horn, and steep inclines a⁴ a⁵ to its front and rear, so as to fulcrum the link on the ridge some two-thirds of its length, being thus caused to project in front thereof. I thus give the link a constant tendency to fall at the moment when the chain-link g is removed from the staple-arm I.

Having thus described my invention, what I claim as new is—

1. The combination, with link F, having chain G g, of staple I J, slide H, and sliding draw-bar, having the top incline a, as and for the purpose described.

2. The combination, with the sliding draw-bar B having top incline a, of the sliding bar H, for releasing the link and allowing it to fall into position to couple two cars together when the draw-bars of the same are brought together, substantially as and for the purpose specified.

3. The combination, with the link, of a transverse ridge, a³, passing just behind the horn of the draw-bar, and the inclines a⁴ a⁵ on opposite sides thereof, as and for the purpose specified.

DAILY S. MOORE.
